UNITED STATES PATENT OFFICE

2,341,477

APPARATUS FOR INTERNALLY COATING CONTAINERS

Paul E. Pearson, Chicago, Ill., assignor to Continental Can Company, Inc., New York, N. Y., a corporation of New York

Application April 10, 1942, Serial No. 438,478

14 Claims. (Cl. 91—45)

The invention relates generally to the art of coating, and primarily seeks to provide a novel apparatus for spraying the insides of containers intended for the packaging of products for the market with a suitable protective coating material, or more specifically, to provide certain new and useful improvements in spraying machines of the type disclosed by Paul E. Pearson in the co-pending application for U. S. Letters Patent Serial No. 225,040, filed on August 15, 1938.

Many products, such as beer, wine, carbonated water, grape juice, and cranberry juice, cannot be packaged in metal cans unless a protective coating or lining is employed to completely insulate the products from the metal of the cans. The invention, therefore, seeks to provide a simplified machine structure in which cans can be efficiently and economically sprayed internally and thereby provided with a smooth and evenly distributed protective coating without likelihood of marring the applied coatings or can surfaces with coating drip.

In its more detailed nature, the invention resides in the provision of a machine of the character stated in which is included a spray confining housing or casing, a pocketed turret which is indexed, station-by-station, about a horizontal axis within the housing, means for feeding containers one-by-one into the turret, novel means for imparting rotation to containers in each pocket as it is presented at the bottom or spraying station, and spray means and novel actuating devices therefor for reciprocating the spray means into and out of the containers at the spray station, said machine also including novel adjustable parts for adapting the machine for the spraying of containers of different sizes.

Another object of the invention is to provide a machine of the character stated, in which is included novel lever and cam actuating devices for imparting reciprocation to the spraying means and including means for varying the stroke limits of the spray means reciprocations.

Another object of the invention is to provide a novel machine structure of the character stated including a novel yieldably mounted disk for imparting rotation to the container at the spraying station.

Another object of the invention is to provide a novel machine structure of the character stated, in which is included a novel means for preventing operation of the spray when no container is present to be sprayed, said no container no spray means including the container driving disk as a part thereof.

With the above and other objects in view which will more fully appear, the nature of the invention will be more clearly understood by following the description, the appended claims, and the several views illustrated in the accompanying drawings.

In the drawings:

Figure 1 is a front face view illustrating the machine.

Figure 2 is a plan view of the machine, parts being broken away and others being shown in horizontal section.

Figure 3 is a vertical cross section taken on the line 3—3 on Figure 1.

Figure 4 is a vertical longitudinal section taken on the line 4—4 on Figure 3.

Figure 5 is a horizontal section taken on the line 5—5 on Figure 4, the turret and its housing being removed for purposes of clarity.

Figure 6 is a rear face view of the machine, the turret and its housing being removed for purposes of clarity.

Figure 7 is a fragmentary face view of the turret housing at the position of the delivery opening therein.

In the machine herein illustrated as an example of embodiment, there is included a base structure 5 upon which is supported a spraying mechanism housing structure 6 wherein is mounted a main cam shaft 7 which is rotatably supported in suitable bearings 8. It will be observed by reference to Figure 4 of the drawings that both ends of the shaft 7 project from the housing structure 6.

A plate cam 9 is secured to one extended end of the shaft 7 and is equipped at its outer face with a generally heart-shaped actuator groove 10 which includes a concentric dwell portion 11 extending about approximately 110°. An indexing cam 12 is longitudinally-adjustably secured, as at 13, on the shaft 7 within the housing structure 6, and this cam is a well known form of indexing cam and includes the usual indexing groove 14. At its other extended end, the shaft 7 carries a spray control valve actuating cam structure generally designated 15 and comprising a driving disk 16 secured upon the end of the shaft and two cam plates 17 which are adjustably secured to the disk, as at 18, and which include outwardly projected concentric dwell portions or crests 19. It will be obvious by reference to Figures 4 and 6 of the drawings that by adjusting the plates 17 relatively about the axis of the shaft 7 the extent of the effective crest or dwell portion presented collectively by the individual crests 19 can be

varied so as to vary the duration of each spraying interval.

A driving rotor 20 is keyed to the shaft 7 within the housing structure 6, and a worm wheel 21 is freely mounted on said rotor. The worm wheel is normally driven by the rotor through an overload release means including the driving balls 22 which engage in the well known manner in seats in the worm wheel 21, being yieldably held in said seats by the spring pressed, longitudinally slid able ring 23. It will be obvious that rotation imparted to the worm wheel 21 will normally be transmitted to the shaft 7 through the overload release means, but upon imposition of an overload tending to hold the shaft 7 against rotation, 15 the balls 22 will be displaced from their seats and the worm wheel 21 permitted to rotate freely about the shaft.

A driver shaft 24 is rotatable in bearings 25 provided therefor in the housing structure 6, and this shaft carries a driver worm gear 26 which meshes with and imparts rotation to the previously mentioned worm wheel 21. The shaft 24 is extended at both ends outside the housing structure 6. At one extended end the shaft 24 carries a large pulley 27 which is driven by a belt 28 from the driving pulley of the motor 29 which is adjustably supported, as at 30, on the housing structure.

The housing structure 6 is equipped with a bearing extension portion 31 and a turret shaft 32 is rotatably supported in bearings 33 in said extension portion, one end of the shaft being extended into the housing structure 6 and the other end extending beyond the extremity of the extension portion 31 in the manner best illustrated in Figures 3 and 5 of the drawings. Within the housing structure 6, the shaft 32 has affixed thereto an indexing disk 34 equipped with a plurality of equidistantly spaced rollers 35 which engage in the indexing groove 14 of the cam 12 so that the rotation of said cam will be transmitted in the form of station-to-station indexing movement to the turret shaft 32. It is to be understood that as many indexing rollers 35 are provided on the disk 34 as there are stations on the turret structure to be described hereinafter, there being six in this particular illustration.

At its extended end, the shaft 32 carries a turret disk 36 which is best illustrated in Figures 1 and 3 of the drawings and is equipped with six equidistantly spaced peripheral pockets 37. Each of the pockets is defined in part by three cross bearings 38 in which are mounted shafts 39 carrying supporting rollers 40 at the ends thereof which project beyond the bearings 38. The six rollers associated with each pocket are so related that they will engage the peripheral surface of the cans or containers 41 between the outwardly turned end flanges 42 thereof.

It will be apparent by reference to Figures 1, 2 and 3 of the drawings that the turret rotates within a spray confining housing 43, said housing being supported, as at 44, on the base structure and also upon the extended end of the housing bearing extension portion 31. The housing is provided with a container receiving opening 45 at the top thereof and a container discharging opening 46 slightly more than one station beyond the lowermost spraying station. See Figures 1 and 7. The whole front face of the housing 43 is open so that free access may be had to the interior thereof, and this face opening is normally closed by a face plate or door 47 which is hingedly supported on the housing proper, as at 48, and is

normally secured in its closed position by a latch equipment 49.

The casing or housing 43 also includes a spray nozzle movement accommodating opening 50 in the rear face thereof in alignment with the turret pocket positioned at the lowermost spraying station, as illustrated in Figures 1 and 3, and the face plate or cover 47 also includes an opening which registers with the spraying station and which is normally closed by a hinged closure 51.

The casing or housing 43 also includes a drain opening 52 at the bottom thereof, directly beneath the spraying station, and this opening may deliver into a collector 53, and a suitable vapor draw-off duct or outlet 54 may be provided in said collector in the manner clearly illustrated in Figure 3.

Containers to be spray coated internally within the machine are fed vertically downwardly into the machine from the feed line 55 through upstanding guide standards in the manner clearly illustrated in Figures 1, 2 and 3 of the drawings; the single standard 56 being provided at one side, and two spaced standards 57 being provided at the opposite side. The standard 56 is laterally-adjustably mounted upon the housing, as at 58, and the standards 57 are adjustably mounted, as at 59, so that the spacing between the standards 57, and also the spacing between the pair of standards 57 and the single standard 56, can be varied to accommodate the feeding of containers of different sizes.

A timing screw 60 is rotatably supported in vertical position in the standard 56 and serves to control or time the delivery of the individual containers into the individual turret pockets. The screw is driven through a bevel gear couple 61 to which rotation is imparted through sprocket and chain connections 62 which are in turn driven through meshing spur gears 63 and the sprocket and chain connections 64 from the cam shaft 7.

The spaced standards 57 serve to support a rock shaft 65 to which is affixed a guide 66 which opposes the timing screw 60 in spaced relation and is yieldably urged toward the screw by the weighted arm 67 in a manner well known in the art.

At its discharge opening 46 the casing or housing 43 is equipped with a pair of sprayed container supporting rails 68 which are mounted in adjustably spaced relation, as at 69, on brackets 70 secured to the housing. The brackets 70 also support side or end guides 71. Stripper guides 72 which merge into upper guide rails 73 also are laterally-adjustably supported, as at 74, on brackets 75, and these serve to strip sprayed containers from the turret pockets as they are moved past the discharge opening 46 and to guide movement of the containers over the supporting rails 68. See Figures 1 and 7.

It will be observed by reference to Figures 1 and 3 of the drawings that while the containers are positioned in the turret pockets in passing from the receiving opening 45 to the discharge opening 46, they are guided and held in said pockets by guide rails 76 secured to housing lugs 77.

As has been previously stated, the spraying of the containers interiorly takes place at the bottom of the casing or housing 43, and at this station the containers presented individually in the indexed turret pockets are rapidly rotated by the continuously driven, yieldably mounted 75 driving disk 78 which preferably is formed of

rubber. The disk is supported at the forwardly projected end of a shaft 79 which is supported in a longitudinal bearing 80 carried at the free ends of a pair of arms 81 projecting from the bearing sleeve 82. The sleeve 82 is disposed in parallel spaced relation to the bearing 80 and is rockable about a shaft supported in bearings 83 mounted, as at 84, upon the housing structure 6. A crank arm 85 projects from the sleeve 82 in the manner clearly illustrated in Figures 1, 4 and 5 of the drawings, and it will be observed that the free end of the arm is disposed between an underlying adjustable stop 86 and an overlying compression spring 87. The stop and spring are carried by a bracket 88 which is secured to the housing structure 6.

In order to provide a suitable drive for the container rotating disk 78, a driver gear 89 is mounted on the shaft extending from the sleeve 82, and this gear drives an idler gear 90 which is supported on one of the arms 81 and meshes with an imparts rotation to the gear 91 fixed to the driving disk carrying shaft 79. A pulley 92 is secured to rotate with the driver gear 89 and has rotation imparted thereto by a belt and pulley connection 93 with the driver shaft 24. See Figures 1, 4 and 5 of the drawings.

A spray gun 94 is reciprocable through the casing or housing opening 50 in the position best illustrated in Figures 3, 4 and 6 of the drawings. This spray gun may take the form of the gun shown in the co-pending Pearson application, Serial No. 225,040, filed August 15, 1938, which has been referred to hereinbefore, or any other approved form can be used. This gun may also be supplied and controlled in the manner illustrated in said co-pending application and for this reason it is thought to be unnecessary to dwell in detail herein upon the specific form of the spray gun, the supply lines leading thereto, or the specific form of the valve by which the operation of the gun is controlled.

The fully retracted position of the spray gun is illustrated in Figure 3 of the drawings, and it will be observed that in this position the spray nozzle end 95 of the gun is projected a short distance into the casing but will be clear of the path of travel of the containers 41 being indexed station-by-station on the turret. The spray gun is vertically-adjustably mounted, as at 96, on a bracket 97 which depends from a slide 98. The slide 98 is slidable horizontally toward and from the housing opening 50 in a suitable guide structure 99 secured to the housing 6 in the manner clearly illustrated in Figures 3 and 4 of the drawings. The slide is link-connected, as at 100, to the lower end of a long actuator arm 101 which is pivotally supported, as at 102, at its upper end on the housing 6. Another, short actuator arm 103 is provided and is pivotally supported at its upper end, as at 104, on the housing 6. The arm 103 is disposed in generally parallel relation to the arm 101 and is connected to the arm 101 by a thrust link 105. The link 105 is connected to the arm 101 by a fixed pivot, but the connection of this link with the actuator arm 103 is by an adjustable pivot connection 106, and is best illustrated in Figure 3. The short arm 103 is provided with a roller 107 which engages in the plate cam groove 10, 11. It will be obvious that as the cam 9 rotates, swinging movement will be imparted to the link-connected arms 101 and 103 and will be transmitted to the slide 98 in the form of straight line, reciprocatory movement. By adjusting the position of the pivotal connection 75

106, the length of the stroke imparted to the slide 98 and the spray gun 94 supported thereon can be varied according to the size of containers being spray coated.

5 The driving disk 78 rotates within a confining and protection boot 108 suspended from the guide rails 76 in the manner clearly illustrated in Figure 3, and by reason of the provision of this boot, the disk is protected from spray contact, and all danger of the disk becoming hardened by coating accumulation is avoided.

It will also be apparent by reference to Figures 1, 3 and 4 of the drawings that the spring equipment 87 yieldably holds the arm 85 downwardly, and the driving disk 78 is thus yieldably projected against the containers which are moved into contact with the constantly rotating disk at the spraying station. By thus yieldably pressing the driving disk against the containers supported by the pocket rollers 40, efficient driving of the containers is provided for regardless of whether they are perfectly round or include slightly out of form or flattened portions.

As in the co-pending Pearson application hereinbefore referred to, the timing and duration of the spray is controlled by a valve 109 and the adjustable cam structure 15 hereinbefore referred to. Since this valve structure is disclosed in detail in the co-pending Pearson application, the details of construction thereof will not be dwelt upon herein. The line supplying atomizing air to the valve is indicated at 110 and the line for directing this air from the valve to the gun is indicated at 111. The line for supplying needle valve actuating air to the valve is indicated at 112, and the line for directing this air to the gun, and for at the proper time exhausting the gun under control of the valve, is indicated at 113. The tappet valves within the valve structure are 35 suitably actuated by the tappet lever 114 which is pivoted, as at 115, on the valve casing and equipped with a roller 116 for engaging the control cam structure 15.

A no container no spray control means is provided and includes a latch arm 117 having a latch member 118 yieldably mounted thereon, as at 119, in position for engaging with a latch 120 projecting from the tappet lever 114. The pivotally mounted latch arm 117 is connected by a thrust link 121 with the free end of the arm 85 projecting from the driving disk mounting. See Figures 1 and 6.

Whenever the driving disk 78 is displaced downwardly by contact with a container presented at the spraying station as illustrated in Figure 3, the free end of the arm 85 will be displaced upwardly away from the stop 86 against the action of the spring 87, and this upward displacement of the arm end will act through the thrust link 121 to lift the latch arm 117 and displace the latch 118 out of the path of movement of the latch 120 on the tappet lever 114, thus permitting normal operation of the tappet lever 114 by the control equipment 15. Whenever no container is presented at the spraying station, however, the driving disk 78 and the arm 85 will not be so displaced and the latch 118 will project into the path of travel of the tappet lever latch 120 and the tappet lever 114 will be secured in the position illustrated in Figure 6 so that rotation of the cam structure 15 can have no effect to operate the tappets of the valve. Thus no spraying action can take place when no container is presented to be sprayed at the spraying station.

In operation, the open ended containers to be

sprayed are lowered one-by-one in properly timed and spaced relation so as to be received in the turret pockets in the manner clearly illustrated in Figure 1. As the indexing of the turret proceeds, the containers will be individually presented at the spraying station at the bottom of the casing.

Each time a container is presented at the spraying station, it engages and slightly displaces the driving disk 18 and is rapidly rotated thereby. While the turret is at rest, and with a container to be sprayed rapidly rotating at the spraying station, the arms 101 and 103 will be swung by the cam 9 to reciprocate the slide 98 and cause the spraying nozzle end 95 of the spray gun to be projected into or through the container and then again retracted to the normal position illustrated in Figure 3. By proper adjustment of the cam plates 17 of the control cam structure 15, the actual spraying interval can be made to occur during any desired portion of the nozzle reciprocation.

As the indexing of the turret is continued, each sprayed container will be ejected by the stripper guides 72 and stripped from the turret pockets and caused to be discharged through the casting opening 46 and between the discharging guides 68, 71 and 73.

It is of course to be understood that the details of structure and arrangement of parts may be variously changed and modified without departing from the spirit and scope of the invention.

I claim:

1. In container body spraying apparatus, a turret rotatable about a horizontal axis and having peripheral pockets therein for receiving individual container bodies, means for rotating the turret step-by-step, a housing encasing the turret for completely confining the spray and having a restricted opening therein aligned with the bottommost stop station of the turret, means for feeding container bodies to the pockets at an upper portion of the housing, a spray nozzle having a spray head constantly maintained within the housing and being reciprocable in said opening into and out of container bodies for spraying them internally, and means for reciprocating said spray head.

2. In container body spraying apparatus, a turret rotatable about a horizontal axis and having peripheral pockets therein for receiving individual container bodies, means for rotating the turret step-by-step, a housing encasing the turret for completely confining the spray and having an opening therein aligned with a stop station of the turret, means for feeding container bodies to the pockets, a spray head reciprocable through said opening into and out of container bodies for spraying them internally, means for reciprocating said spray head, and a yieldably mounted continuously rotating driver disk engaged by each container at the spraying station and effective to impart rotation to the container bodies as they are being sprayed.

3. In container body spraying apparatus, a turret rotatable about a horizontal axis and having peripheral pockets therein for receiving individual container bodies, means for rotating the turret step-by-step, a housing encasing the turret for completely confining the spray and having an opening therein aligned with the bottommost stop station of the turret, means for feeding container bodies to the pockets at an upper portion of the housing, a spray head reciprocable through said opening into and out of container bodies for

spraying them internally, means for reciprocating said spray head, and a yieldably mounted continuously rotating driver disk engaged by each container at the spraying station and effective to impart rotation to the container bodies as they are being sprayed.

4. In container body spraying apparatus, a turret rotatable about a horizontal axis and having peripheral pockets therein for receiving individual container bodies, means for rotating the turret step-by-step, a housing encasing the turret for completely confining the spray and having an opening therein aligned with the bottommost stop station of the turret, means for feeding container bodies to the pockets at an upper portion of the housing, a spray head reciprocable through said opening into and out of container bodies for spraying them internally, means for reciprocating said spray head, a yieldably mounted continuously rotating driver disk engaged by each container at the spraying station and effective to impart rotation to the container bodies as they are being sprayed, guide rails confining container bodies in the turret pockets while moving to the spraying station, and a protecting boot at least partially surrounding the disk and supported by said rail.

5. In a container body spraying apparatus, a turret having peripheral pockets therein in which to rotatably support container bodies to be sprayed, a spraying station, means at the spraying station for interiorly spray-coating containers, means for indexing the turret to individually present containers at said station, a rotary disk engageable with containers presented at the spraying station for imparting rotation thereto, and spraying means operation controlling devices controlled by the position of the disk, that is whether the disk is in or out of engagement with a container to be sprayed, so as to prevent actuation of the spraying means when no container is present to be sprayed.

6. In a container body spraying apparatus, a turret having peripheral pockets therein in which to rotatably support container bodies to be sprayed, a spraying station, means at the spraying station for interiorly spray-coating containers, means for indexing the turret to individually present containers at said station, a rotary disk engageable with containers presented at the spraying station for imparting rotation thereto, means yieldably supporting said disk for displacement by contact with a container moving into the spraying station, spraying means operation controlling devices, and means rendering said devices ineffective except when said supporting means is displaced by container contact.

7. In a container body spraying apparatus, a turret having peripheral pockets therein in which to rotatably support container bodies to be sprayed, a spraying station, means at the spraying station for interiorly spray-coating containers, means for indexing the turret to individually present containers at said station, a rotary disk engageable with containers presented at the spraying station for imparting rotation thereto, means yieldably supporting said disk for displacement by contact with a container moving into the spraying station, spraying means operation controlling devices including an actuator cam, a spray controlling valve and a valve actuator operated by said cam, latch means normally effective to hold the valve actuator out of position for effectively contacting said cam, and means actuated as an incident to movement of displacement 75 of the disk for rendering said latch means in-

effective and permitting the valve actuator to be operated by said cam.

8. In a container body spraying apparatus, a turret having peripheral pockets therein in which to rotatably support container bodies to be sprayed, a spraying station, means at the spraying station for interiorly spray-coating containers, means for indexing the turret to individually present containers at said station, a rotary disk engageable with containers presented at the spraying station for imparting rotation thereto, a lever arm structure whereon said disk is rotatably supported, means pivotally mounting said lever arm structure, spring means constantly urging the lever arm structure toward the turret to place the disk in position for engaging and being displaced slightly by a container moving into the spraying station, adjustable means for limiting movement of said lever arm structure toward the turret, spraying means operating devices, means operable by movement of said lever arm structure for preventing effective operation of said spraying means operating devices except when a container is being engaged and rotated by said disk, and means for imparting rotation to said disk.

9. In a container body spraying apparatus, a turret having peripheral pockets therein in which to rotatably support container bodies to be sprayed, a spraying station, means at the spraying station for interiorly spray-coating containers, means for indexing the turret to individually present containers at said station, a rotary disk engageable with containers presented at the spraying station for imparting rotation thereto, a lever arm structure whereon said disk is rotatably supported, means pivotally mounting said lever arm structure, spring means constantly urging the lever arm structure toward the turret to place the disk in position for engaging and being displaced slightly by a container moving into the spraying station, adjustable means for limiting movement of said lever arm structure toward the turret, spraying means operating devices, means operable by movement of said lever arm structure for preventing effective operation of said spraying means operating devices except when a container is being engaged and rotated by said disk, and means for imparting rotation to said disk.

10. In container body spraying apparatus, a turret rotatable about a horizontal axis and having peripheral pockets therein for receiving individual container bodies, means for rotating the turret step-by-step, a housing encasing the turret for completely confining the spray and having an opening therein aligned with the bottom-most stop station of the turret, means for feeding container bodies to the pockets at an upper portion of the housing, a spray head reciprocable through said opening into and out of container bodies for spraying them internally, and means for reciprocating said spray head, said feeding means including a pair of guide standards extending upwardly from the housing in spaced relation, means for adjustably mounting said standards on the housing so that their spaced relation can be varied, a single standard centrally opposing the pair of standards, means for adjustably mounting and supporting the single stand-

ard on the housing so that it can be moved toward or from the pair of standards, and a timing screw supported on said single standard.

11. In container body spraying apparatus, a 5 turret rotatable about a horizontal axis and having peripheral pockets therein for receiving individual container bodies, means for rotating the turret step-by-step, a housing encasing the turret for completely confining the spray and having an opening therein aligned with the bottommost stop station of the turret, means for feeding container bodies to the pockets at an upper portion of the housing, a spray head reciprocable through said opening into and out of container bodies for spraying them internally, and means for reciprocating said spray head, said feeding means including a pair of guide standards extending upwardly from the housing in spaced relation, means for adjustably mounting said standards on the housing so that their spaced relation can be varied, a single standard centrally opposing the pair of standards, means for adjustably mounting and supporting the single standard on the housing so that it can be moved toward or from the pair of standards, a timing screw supported on said single standard, a shaft traversing and supported by the pair of standards, and a guide wall yieldably opposing the timing screw and swingably mounted on said shaft.

12. In a container body spraying apparatus, a 10 turret having peripheral pockets therein in which to rotatably support container bodies to be sprayed, a spraying station, means for indexing the turret to individually present containers at said station, means for imparting rotation to container bodies presented at said station, a spraying nozzle, and means for reciprocating said nozzle into and out of container bodies at said station for interiorly coating them, said last named means comprising a slide on which said nozzle is carried, means guiding movement of the slide, a motor, and adjustable lever and link connections between the motor and the slide for imparting variable stroke movements to said slide.

13. In a container body spraying apparatus, a 15 turret having peripheral pockets therein in which to rotatably support container bodies to be sprayed, a spraying station, means for indexing the turret to individually present containers at said station, means for imparting rotation to container bodies presented at said station, a spraying nozzle, and means for reciprocating said nozzle into and out of container bodies at said station for interiorly coating them, said last named means comprising a slide on which said nozzle is carried, means guiding movement of the slide, a thrust link, a swingable actuator arm, means adjustably connecting the link to the actuator arm so that a selected amount of throw can be imparted to the link by the swinging arm, means connecting the link with the slide, and means for swinging the actuator arm.

14. A spraying apparatus structure as defined in claim 13, in which the means for swinging the actuator arm comprises a rotary cam having a generally heart-shaped groove therein and a roller projecting from the actuator arm and engaging in said groove, said groove also including a concentric dwell portion for holding the spraying nozzle for an interval in the retracted position during each indexing movement of the turret.

PAUL E. PEARSON.
